UNITED STATES PATENT OFFICE.

WESLEY G. WINANS, OF DETROIT, MICHIGAN, ASSIGNOR TO ORRIN C. CASTLEOF, OF AKRON, OHIO.

DOOR HOLDER.

Application filed January 12, 1920, Serial No. 351,036. Renewed July 13, 1922. Serial No. 574,826.

To all whom it may concern:

Be it known that I, WESLEY G. WINANS, a citizen of the United States, residing at Detroit, in the county of Wayne and State 5 of Michigan, have invented certain new and useful Improvements in Door Holders, of which the following is a specification.

This invention has reference to a combined bumper and catch for doors and the 10 like, and the object of this invention is to produce a construction which will silently retard the movement of the door, gate, lid or the like, and which will hold it stationary. Another object of the invention is to 15 provide means which will positively lock the door or the like, and my invention is also intended to provide means for overcoming the sagging of the door, and to secure various advantages hereinafter set 20 forth.

In the drawings in which I have shown means embodying my invention by way of example:—

Figure 1 is a sectional view of a device according to my invention, as applied to a door;

Figure 2 is a sectional end view thereof;

Figure 3 is a perspective view thereof with the cooperating parts slightly separated.

Figure 4 is an enlarged fragmentary sectional side view of a modified construction.

Figure 5 is a modified construction of the socket part of my invention in sectional view and top plan view respectively;

Figure 6 illustrates another modification showing improved means of mounting one of the cooperating members of the device upon the door.

A represents the door or lid or the like which is hinged at one edge to the jamb B, the opposite edge of the door being adapted to lie adjacent to the other door jamb B'. The spring A' secured to the door A and the jamb B tends to resiliently close the door. My combined bumping and catching device consists broadly speaking of two members which are respectively secured to the door or other swinging means and 45 to the stationary base or enclosing means of said swinging means or closure, the said cooperating members being broadly speaking a spring acting socket-like clip, and a substantially cylindrical stud member engageable with said clip, means being pro-

vided on one of said members, and engageable with the other cooperating member for locking said members in the inter-engaging or closed position. The substantially cylindrical stud member D which 60 may be formed of a non-metallic elastic material such as hard rubber, is here shown as being mounted on the door jamb B' by means of a base C having an extension C' upon which the stud, roller or the like D 65 is secured, the extension C' being of smaller diameter than the base C and threaded at its outer end for engagement with a nut C², the projecting shoulder of the base C serving to retain the stud member D in 70 place. The spring acting or resilient socket member is here shown as being for instance mounted upon the door A, the said socket being in form of a resilient substantially U-shaped clip F which is secured to the 75 door by the screw E, and is adapted to co-operate with the cylindrical stud member D upon the jamb B', the clip F being inturned as at F' sufficiently to retard the movement of the door, and to retain the member D in engagement therewith.

For the purpose of locking the socket and stud members D and F in the position of engagement a preferably hook shaped clip or other locking or retaining member is 85 connected to one of the cooperating stud-and-socket members referred to. In the construction shown in Figures 1 to 4 of the drawing, the said locking and retaining member is formed by a resilient hook-shaped clip G, mounted upon the extension C' near the securing nut C², and rotatable on said extension C'. The member G has an inturned flange G' extending over the cylindrical stud member D and adapted to 95 engage the resilient socket member or spring clip F adjacent its point of attachment to the door, as shown by the dotted lines in Figure 2.

Another feature of the invention resides 100 in the locking means for the rotatable or pivotally secured locking member G whereby the latter may be retained in any desired position. As shown in Figure 4 this locking means comprises a plate H, preferably 105 of metal, and set in the cylindrical stud member D and having the outwardly extending projection H'. The resilient locking member G is provided with the recess G² adapted to cooperate with the projec- 110

tion H' to hold the resilient member G in position. It is to be understood that any number of plates H may be employed, depending upon the various desirable positions for retaining the resilient locking member G.

In operation, if the door is opened the spring A' tends to close the same, and in the closing movement the cylindrical stud member D is engaged by the resilient clip or socket member F to close the door silently and to retard the closing movement. To lock the door in the closed position the resilient clip or locking member G may be turned to engage the clip F at some position near the point of attachment of said part F with the door. Furthermore than that, the metallic or other plate H may be used to retain the resilient latch or locking clip G in place so as to prevent any accidental disengagement or engagement thereof with the socket member F.

It is obvious that I may also secure the socket member F to the stationary part or jamb B, while the substantially cylindrical stud member D may also be secured to the door or other swinging and closing means.

As the sagging of the door will interfere with the exact engagement of the cooperating stud-and-socket members, I have provided means for adjusting any or both of these cooperating members in the position of engagement, such means consisting of a slot in the base to which such member is secured. In Figure 5 I have shown the stud member D as being adjustably mounted in a longitudinal slot of the base C, the member being locked in the adjusted position by a nut K threaded upon the end J of the extension C' which projects through the raised or angularly projecting slotted part of the base C, the nut K clamping the base between the stud D and said nut. A similar adjustment may be provided for the socket member if the latter is mounted upon the door A.

In order to hold the door or other swinging closing means in the open position I provide a bracket or an arm L (Figure 6) which may be attached at one end to the door, as by means of a projection or an angle M on said door to which the arm L is secured by means of a bolt or the like N.

A resilient socket member or spring clip P may be secured to the free end of arm or bracket L being here shown as attached to the inside of the hook shaped end part of said arm. The stud part O which is secured to the stationary member or frame of the door is engageable with the clip P. It may be provided with a pin or projection R which enters a longitudinal slot in the arm L, and preferably in the middle line of said arm. When the door is opened the pin R slides along said slot until the clip P engages the substantially cylindrical stud member O. The arm L may be pivotally connected to the door or to the bracket M; but this is not absolutely necessary.

While in Figures 1 to 4 the combined bumper and catch is shown as being employed in the closed position of the door, it is evident that when the parts are of suitable dimensions it may also be used in the open position thereof.

What I claim is:—

1. In a door holder, the combination of movable and stationary building elements, a socket comprising a flexible band adapted to be screwed to the movable element, a stud adapted to be secured to the stationary element, a roller on the stud to fit within the socket and be grasped by its sides, a clip journaled on the stud and adapted to be swung over the sides of the socket sides, and a detent carried by the roller and adapted to engage the clip and lock the roller in the socket and means cooperable with the clip to hold the door in open position consisting of a plate having one end connected with the door and its other end movable upon the stud of the roller.

2. In a door-holder, the combination with a door and jamb therefor, a base secured to the jamb and carrying a stud, a roller mounted on said stud, an angle bracket secured to said door, a plate having one end pivoted to said bracket and having its other end formed with a bend, said plate being formed with a slot engaging and movable upon the stud of the roller and a spring clip operating in conjunction with said plate and engaging the said roller.

In testimony whereof I affix my signature.

WESLEY G. WINANS.
